LEAKPROOF RECESSED BOTTOM CARTON
George V. Skowronski, Neenah, Wis., assignor to American Can Company, New York, N.Y., a corporation of New Jersey

Filed May 26, 1961, Ser. No. 112,987

2 Claims. (Cl. 99—171)

This invention relates to a leakproof carton provided with a recessed bottom. More specifically, the invention may be used advantageously for the display of packaged food products.

Cartons and containers having recessed bottoms have been employed for a variety of purposes. For instance, paper cups which have the bottom recessed, are used for hot drinks with the recessed bottom preventing contact with a surface susceptible to heat damage. Round tubs or pails with recessed bottoms have been employed in the packaging of cottage cheese and ice cream to protect the product from ice or water in the bottom of the storage area. Present square or rectangular recessed bottom cartons are available but generally have the shortcoming of not being suitable for packaging liquids. The construction of the cartons is such that the corners of the carton have a tendency to leak. While the round tub is leakproof, it has the disadvantages of being uneconomical with regard to storage space as well as having more limited printing areas.

Ideally, a recessed bottom carton or container should, in order to provide the desired versatility for food packaging, include the following features. The upright carton should be leakproof to the top edges thereof and capable of maintaining its leakproofness for a period of time. When a tight fitting closure is applied to the top, the carton should be leakproof when changed to an inverted position. A square or rectangular shape is desirable since it provides economy of storage space as well as increased printing areas. The strength of the wall portions extending below the bottom of the carton should be sufficient to resist appreciable downward pressures on the carton without collapsing. For economy of operation in setting up the carton a single blank is ideal to reduce the number of steps required. Finally, the appearance of the finished carton should be suitable for display purposes thereby enhancing sales appeal.

It is a primary object of the present invention to provide a leakproof rectangular, recessed bottom carton that can readily be set up from an integral blank.

Another object of the present invention is to provide a rigid carton which is adapted to receive a tight fitting closure to make a totally leakproof package.

Still another object of the present invention is to provide a sealed carton having multiple printing areas which fully utilizes storage space and

Yet another object of the present invention is to provide a reinforced leakproof carton having a neat appearance which enhances the saleability of the packaged product.

A further object of the present invention is to provide a carton which has a tight fitting closure suitable for reuse and numerous reclosings.

According to the present invention a tapered rectangular leakproof carton with a recessed bottom is constructed from an integral blank. At least a double thickness in

2

all of the carton walls provides a reinforced construction which resists forces which would crush or distort a carton of weaker construction. The finished carton in an upright position has no single or rough edges apparent because of the particular fold pattern of the blank employed in making the carton. Further, the carton blank need only be coated on one side for purposes of heat-sealing and leakproofness. The particular fold pattern is such that in the finished upright carton the inside surfaces of the carton as well as the visible outside surfaces of the carton have the protective coating thereon. Integral corner webs which extend to the upper edge of the side walls insure leakproofness in the finished carton, while a tight fitting closure in pressure contact with the lips or upper edge portions of the side walls maintains leakproofness when the carton is inverted.

Further details, advantages and objects of the present invention will be apparent from the following specification and appended drawings wherein:

20 FIGURE 1 is a plan view of an integral blank suitably cut and scored to form a rectangular leakproof carton,

FIGURE 2 is a plan view of the blank shown in FIGURE 1 folded upon itself,

25 FIGURE 3 is a plan view of the blank shown in FIGURE 2 partially set up,

FIGURE 4 is a fragmental perspective view of the same partially set up blank at a further stage in being set up,

30 FIGURE 5 is a perspective view of the completed carton,

FIGURE 6 is a sectional view of the set up carton taken along 6—6 of FIGURE 4, and

35 FIGURE 7 is a perspective view of the completed carton containing a food commodity and sealed with a tightly fitting closure.

40 Referring to FIGURE 1, the carton is made of a single foldable blank "A" of flexible material, such as paper-board, provided with a gloss wax composition coating or other suitable materials such as polyethylene, rubber hydrochloride and the like, suitable for heat sealing. The blank is divided by score lines 10a, 10b—19 into hingedly connected panels, flaps and webs including bottom panel 30, inner side panels 31, 38, outer side panels 32, side panel flaps 35, 40, edge flaps 33, outer edge flaps 34, 45 web portions 36, 37 and lip panels 39.

46 After the blank has been formed, the first step in forming the carton is to infold outer edge flaps 34 and edge flaps 33 about score lines 10a and 10b, respectively, to lie flat on the adjacent carton blank areas hingedly connected thereto. Next, outer side panels 32 with side panel flaps 35, 40 connected thereto by score lines 16 are infolded about score lines 11 to lie in superposed relationship on inner side panels 31 as shown in FIGURE 2. This view shows the bottom or outside of bottom panel 30.

51 In setting up the carton, the folded blank shown in FIGURE 2 is turned over and superposed inner and outer side panels 31, 32 are infolded about score lines 12 with web portions 36, 37 hingedly connected together by score lines 18 folded outwardly. The infolding is continued until the lateral edges of inner side panels 31 and 38, defined by score lines 17 and 19, respectively, abut. At this stage, which is shown in FIGURE 3, web portions 36 and 37 hingedly connected along score

lines 18, lie superposed against side panel flaps 35, 40. The web portions 36 and 37 are then heat sealed together to provide a leakproof body defined by the side panels and bottom panel.

In order to complete the setting up, side panel flaps 40 with web portions 36, 37 and outer edge flaps 34 superposed thereagainst are infolded against inner side panels 38 as shown in FIGURE 4. Then side panel flaps 35 with web portions 36, 37, and outer edge flaps 34 superposed thereagainst are infolded about adjacent score lines 16 to lie superposed against the outer surfaces of side panel flaps 40. Finally, upstanding lip panels 39 are folded outwardly about score lines 14 to lie superposed against the upper edges of side panel flaps 35 and 40. Heat and pressure are then applied with lip panels 39 becoming heat-sealed to the upper edges of side panel flaps 35, 40, and side panel flaps 35 becoming heat-sealed to flaps 40. The completed carton having a rigid, leak-proof construction is shown in FIGURE 5.

FIGURE 6 shows in section the bottom construction of the carton. Bottom panel 30 is suspended up from the bottom edges of the carton a distance approximately equal to the difference in height between the inner side panels 31 and the outer side panels 32. This distance can be varied as desired merely by changing the height relationship between the inner and outer side panels. The bottom edges of the carton are reinforced by the doubled thickness of the lower extremities of the carton adjacent to bottom edges. Double thicknesses in all of the carton side walls gives increased strength to the carton tending to prevent distortion due to packing and handling.

FIGURE 7 is a perspective view of the completed carton containing a commodity, for example potato salad, which is an item particularly well suited for vending machine packaging. A tightly fitting groove plastic closure 50 is employed to maintain the freshness of the particular commodity being packaged. In place of the closure 50, a partial overwrap surrounding and adhered to the upper portion of the filled carton may be employed. The degree of opacity of the cover employed obviously depends upon whether or not the carton is used to display the commodity packaged in it.

Although the embodiment described employs paperboard with a heat-sealable coating thereon to obtain leak-proofness, other means of making the carton according to the present invention leakproof may be employed. For instance, the carton blank may be made of uncoated paperboard and the blank set up by applying adhesive to the surfaces of lip panels 39 and side panel flaps 35 and 40. The step of sealing the web portions 36 and 37 together may be omitted. After the carton is completed, a thin membrane of liquid proof material, such as polyethylene, may be applied to the interior surfaces of the carton. Another method would be to spray the interior surfaces of the completed uncoated paperboard carton with a thin plastic film. Since the steps of either adding a membrane to or spraying a plastic film on the inner surfaces of the carton are more costly than employing coated paperboard blanks, the particular embodiment described in detail herein is preferred.

The appearance of the carton according to the present invention can be considerably enhanced if the paperboard blank is laminated with a layer of metal foil. Since in the finished carton only the inside surface of the original blank shows, the foil need be applied only on one surface of the original blank. The side of the original blank opposite the foil may be coated with a heat-sealable adhesive and the carton set up as previously described. The use of a foil covered blank is particularly advantageous for display packaging and when the carton contains a commodity that the consumer will use over a period of time so that the carton will be viewed a number of times.

Although the embodiment as described employs a heat sealable adhesive for securing the side panel flaps and

lip panels, other means such as locks or staples may be employed. For instance, side panel flaps 35 and 40 may have cooperating male and female locking means thereon which when the flaps are infolded engage in locking relationship. The use of staples is advantageous when the carton is constructed of uncoated paperboard and a plastic membrane coated of the inside of the completed carton to render it leakproof.

The present invention provides a web corner carton construction which makes the carton leakproof. When the web portions are sealed together adjacent their connection to the side panels, wicking of the liquid into the upper edges of the web portions is prevented. The rectangular construction provides a larger printing surface than does a round tub. Double thickness side walls of the carton give a carton construction which resists large compression forces such as would be applied to a carton on the bottom of a stack of loaded cartons on trays. Furthermore, a rectangular carton is more economical to store in terms of capacity per amount of storage space required. Also, the integral carton blanks may be set up readily by hand or machinery.

It is to be understood that the size and the shape of the carton and the material from which it is formed may be varied in numerous ways by those skilled in the art without departing from the spirit of the invention.

I claim:

1. A tapered, recessed bottom, leakproof carton formed of a single blank suitably cut and scored to provide a carton having a bottom panel, two pairs of opposed trapezoidal shaped inner side panels of essentially equal configuration hingedly connected to the edges of said bottom panel, a pair of trapezoidal shaped opposed outer side panels hingedly connected to the upper edges 35 of the first pair of said inner side panels and lying superposed thereagainst and extending an appreciable distance below the bottom panel with the side edges of the outer side panels essentially coextensive with the side edges of said inner side panels, two component webs hingedly 40 connected to the adjacent side edges of said inner side panels with each of said webs having a diagonal score line connecting said components and folded to lie superposed against the second of said pair of inner side panels, said web components being sealed together along their hinge 45 connection to the adjacent side edges of the inner side panels, a pair of opposed edge flaps hingedly connected to the bottom edges of said outer side panels and lying in superposed relationship therewith with the upper marginal portions thereof lying between said first pair of inner side panels and said outer side panels, side panel flaps hingedly connected to the side edges of the outer side panels and forming outer side walls lying superposed on the second pair of inner side panels in overlapping 55 relationship, outer edge flaps attached to the bottom edges of the closure flaps and lying in superposed relationship therewith with the upper marginal portions thereof lying between said second pair of inner side panels and said side panel flaps, and a pair of opposed lip panels, hingedly connected to the upper edges of the second pair 60 of inner side panels and lying superposed on the upper marginal portions of the outer side walls, said carton having its inner areas covered with a liquid proof layer.

2. A food package comprising a leakproof recessed bottom container having food products therein; said container being formed of a single cut and scored blank having a bottom panel; two pairs of opposed inner side panels of essentially equal configuration hingedly connected to the edges of said bottom panel; a pair of opposed outer side panels hingedly connected to the upper edges of the first pair of said inner side panels and lying superposed thereagainst and extending an appreciable distance below the bottom panel with the side edges of the outer side panels essentially coextensive with the side edges of said inner side panels; two component webs hingedly connected to the adjacent side edges of said

inner side panels with each of said webs having a diagonal score line connecting said components and folded to lie superposed against the second of said pair of inner side panels, said web components being sealed together along their hinge connection to the adjacent side edges of the inner side panels; a pair of opposed edge flaps hingedly connected to the bottom edges of said outer side panels and lying in subposed relationship therewith with the upper marginal portions thereof lying between said first pair of inner side panels and said outer side panels; side panel flaps hingedly connected to the side edges of the outer side panels and forming outer side walls lying superposed on the second pair of inner side panels in overlapping adhered relationship; a pair of opposed lip

panels hingedly connected to the upper edges of the second pair of inner side panels and lying superposed on the upper marginal portions of the outer side walls; said container having its inner areas covered with a liquid proof layer and having a securely fitting top closure to preserve the freshness of said perishable food.
